Griffiths & Seaton PLLC(57) **CLAIM**

The ornamental design for a display fixture, as shown and described.

DESCRIPTION

FIG. 1 is a top, front perspective view of a display fixture showing our new design;

FIG. 2 is a front view thereof;

FIG. 3 is a rear view thereof;

FIG. 4 is a right side view thereof;

FIG. 5 is a left side view thereof; and,

FIG. 6 is a top view thereof.

The features shown in broken lines are portions of the display fixture forming no part of the claimed design. The bottom view is omitted as the bottom surfaces of the display fixture are unclaimed.
